PACKAGING TRAY

Gilbert R. Chadbourne, Oakland, Maine, assignor to Keyes Fibre Company, Waterville, Maine, a corporation of Maine

Filed Aug. 21, 1969, Ser. No. 18,786

Term of patent 14 years

Int. Cl. D9—99

U.S. Cl. D9—243

FIG. 1 is a top plan view of a packaging tray embodying my new design;

FIG. 2 is a side elevational view of the packaging tray of FIG. 1;

FIG. 3 is a sectional view taken along line 3—3 of FIG. 1; and

FIG. 4 is a fragmental sectional view taken along line 4—4 of FIG. 1.

I claim:

The ornamental design for a packaging tray, as shown.
